UNITED STATES PATENT OFFICE.

GEORGE A. FITCH, OF KALAMAZOO, MICHIGAN.

IMPROVEMENT IN PRIMING CARTRIDGES.

Specification forming part of Letters Patent No. 58,800, dated October 16, 1866.

To all whom it may concern:

Be it known that I, GEORGE A. FITCH, of Kalamazoo, in the county of Kalamazoo and State of Michigan, have invented certain new and useful Improvements in Cartridges; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use the invention, I will proceed to describe it.

My invention consists in a novel means of igniting the powder in the cartridge-case at various points—that is to say, at the front, or front and rear combined, or in the center, as may be desired—and using in combination therewith an accelerating-charge of powder, as hereinafter explained.

It is well known that but a limited quantity of powder can be burned in guns where the cartridge is ignited at the rear of the charge, and that, as the powder in such cases burns at the rear first, the ball leaves the barrel before all the powder is consumed, and consequently a portion of the powder is blown out of the gun unburned. Where the bore of the gun is small, a given quantity of powder will necessarily occupy more longitudinal space in the barrel, and will, of course, require a longer time for its consumption, and in such cases it follows that a still smaller portion of the powder will be utilized, and the ball consequently projected with a decreased power.

To remedy these difficulties I construct the cartridge as shown in the drawings, all of which are longitudinal sectional views of a cartridge, all being modifications of the same general idea.

In Figure 1, A represents the cartridge-case, and B the bullet, united in the usual manner. Within the case A, I secure a longitudinal pin or stem, *a*, which is secured to the center of the base of the case by solder, or in any other suitable manner. This stem *a* is made of such a length that there will be just room enough for a cap, *c*, between its front end and the base of the ball when the latter is inserted in place, as clearly shown in Fig. 1.

It will be seen that when the hammer strikes the base of the case A at the point where the stem *a* is attached, the latter will be driven forward and ignite the fulminate of the cap *c*, which, being at the front of the charge of powder, will inflame the latter at that point, and that, burning from the front backward, none of the powder can escape from the barrel without being burned. When using a cartridge of this style I fill it with two grades of powder, as represented, that in front being coarse or slow-burning, to start the bullet gradually, and thus permit it to take the rising without stripping, and then, as the ball nears the muzzle, the finer powder at the rear takes fire and burns quickly, thus following up the bullet with an accelerating force, besides utilizing the entire quantity of powder used.

Fig. 2 represents a cartridge having the central stem, *a*, and the cap *c* located at the front, the same as in Fig. 1, with the addition of fulminate in the rim or flange, as in the ordinary cartridge. In firing this cartridge, the hammer of the arm must be made to strike the cartridge both at the center of the base, opposite the end of pin *a*, and on the flange *e*, as shown in Fig. 2. To accomplish this the hammer *H* may be provided with the points *o n*, as there represented, or it may have its face extended in a straight line from *o n*, as may be found most expedient.

It will be seen that when thus arranged the powder will be ignited simultaneously at the front and rear, and that when thus burning from both ends double the amount of powder can be burned in the same length of time that could be if burning from one end only. In this case the accelerating-charge of fine powder may be omitted, if desired, as a cartridge thus constructed and ignited will burn all the powder required before the bullet can leave the barrel, especially in long barrels, such as are used by infantry troops. In arms having short barrels, such as carbines and pistols, the accelerating-charge may be found necessary, however.

Fig. 3 represents a cartridge in which I accomplish the same object by igniting the charge at the center. In this case the central stem or pin consists of two parts, the part *a'* being secured to the base of the case A, and the other part, *a*, being secured to the

rear end of the bullet B, as shown clearly in Figs. 3 and 4. A cap, c, is placed on the end of one of the parts of the stem in such a position that when the pin a' is driven forward by the hammer the cap will be forced against the end of the stem a and exploded, thus igniting the powder at the center of the charge, from whence it will burn both forward and backward, thus insuring the burning of the entire charge.

Fig. 4 represents a slight modification of this last style, the front end of the pin a' in this case being made cup-shaped to receive the fulminate, as shown, and thus avoid the necessity of using a cap, which would be more liable to become displaced or lost. It is obvious that this cup form of stem may be used also in the other cases, if desired.

In order to prevent the accidental explosion of the cartridge by handling or transportation, I propose to make the base concave, as shown in Fig. 5, so that there will be no danger of accidentally hitting the stem a and prematurely exploding the charge.

It is also obvious that my invention may be applied to artillery as well as to small-arms, especially in all breech-loading styles of small caliber.

Having thus described my invention, what I claim is—

1. Igniting the cartridge at the front by means of the stem a, in combination with the accelerating-charge, as shown in Fig. 1, and as herein described.

2. Igniting the charge at both front and rear, as shown in Fig. 2, and as herein set forth.

3. Providing a cartridge with the stems a and a', when arranged to act in combination, as shown in Figs. 3 and 4, for the purpose of igniting the charge at the center, substantially as set forth.

GEO. A. FITCH.
